UNITED STATES PATENT OFFICE.

DANIEL W. CAUSEY, OF NORFOLK, VIRGINIA.

SMOKER'S APPLIANCE.

Application filed August 12, 1926. Serial No. 128,791.

This invention relates to smokers' appliances, and more particularly to an improvement in a receptacle which can be conveniently carried by the user to serve as a personal ash tray and receiver for lighted stubs of cigarettes and the like.

One of the objects of the invention is to provide a useful and convenient device which may be conveniently embodied in a neat and attractive form, and which is readily available for use in holding the ashes of cigarettes and the like, as well as furnishing a support for the lighted "smoke".

While devices of this general character have heretofore been used, nevertheless it has been the general custom to combine the feature of a receptacle with either a package of cigarettes or box of matches or some other smoking accessory which has proved to be more or less unpopular. Furthermore, it is essential to provide a device which will receive and hold a lighted stub to extinguish the same in order to meet fire underwriters' requirements. Accordingly, the present invention contemplates a receptacle which will be readily available to the smoker and will encourage the proper disposition of the ashes as well as the lighted stub in a safe and practical manner.

A further object of the invention is to provide a support or rest adapted to be used in connection with receptacles of various types, thereby rendering the invention of special utility in connection with standard metallic packages or receptacles. For example, it is proposed to make a rest or support for the cigarette or the like which is so constructed that the same may be placed in unused compacts or receptacles originally sold containing facial cosmetics.

With the above and other objects in view which will more readily appear as the nature of the invention is better understood the same consists of the novel construction, combination and arrangement of parts herein-after more fully described, illustrated and claimed.

A preferred and practical embodiment of the invention is shown in the accompanying drawings in which:—

Fig. 1 is a perspective view of one embodiment of the invention.

Fig. 2 is a vertical cross sectional view of the device shown in Fig. 1.

Fig. 3 is a detail cross sectional view taken on the line 3—3 of Fig. 1.

Fig. 4 is a detail sectional view of a modification.

Fig. 5 is a detail perspective view of one of the rest units having an adjustable base. 60 Similar reference characters designate corresponding parts throughout the several figures of the drawings.

In carrying the invention into effect it is proposed to employ a receptacle of any desired shape or design the same including two interfitting sections preferably of cup-like form and respectively designated as A and B connected by a hinge C thereby to be opened and closed to provide an air-tight receiver 65 for ashes and lighted stubs. In connection with the sections A and B it may be noted that it is proposed to hingedly connect the same in such a way that when the device is opened for use, both sections will lie flat 70 upon the supporting surface to provide a device that is stable and will readily stay in the position in which it is placed or set.

One of the sections is adapted to carry therewith a rest or rack for supporting the 80 lighted cigarette or the like in a position above the plane of the members when opened up for use. In other words, the rest D is adapted to be folded or collapsed down into the section on which it is mounted by the 85 mere act of bringing the other section in closed relation thereto. As previously indicated, it is the purpose and intent to provide a rest D which may be embodied in the receptacle as a permanent part thereof, or as 90 a unit which may be fitted into any desired receptacle. Therefore, as shown in Fig. 1 of the drawings, the rest D is shown as permanently associated with the section B, as is also true of Fig. 4 which shows a modification of the invention, while in Fig. 5 the 95 unit is shown in the form adapting it for use in connection with various sizes of containers.

Referring more particularly to the type 100 of rest shown in Fig. 1 it will be observed that the same includes a plate or platform 1 pivotally mounted on or carried by the swinging bail members 2 which may be conveniently held to the section B by means of 105 the securing strip or base member E. The ends of this strip E may be conveniently inserted in the usual bead or flange ordinarily formed on boxes or receptacles of the type shown, or on the other hand it may be riveted or otherwise secured in position. For the purpose of holding the platform 1

in an elevated or erect position, the same may be connected at one end with the section A so that when the box is opened the platform will be automatically brought into position for use. Various expedients may be resorted to for automatically erecting the plate constituting a platform, but as shown in Figures 1 and 2 the said platform is preferably connected to the section A by means of the link 3, the said link being anchored in any suitable manner to the section A, as for example, by connecting with the fin or abutment 4. With this arrangement it will be clear that upon the movement of one section of the receptacle with reference to the other, the rest D will be automatically actuated to facilitate the closing of the sections.

As will be observed from Fig. 4 the rest D' is mounted upon base E' and swingingly supported on the bail members 5, similar to the manner in which the rest D is mounted. However, in this embodiment the rest is spring actuated so that when the sections are opened up the rest will automatically elevate to the position shown. While a spring of any suitable type may be used for the purpose indicated, in the embodiment shown a coil spring 6 is conveniently wrapped about the horizontal portion of one of the bails and has one of its ends engaging the vertical portion of the bail, the tension of the spring being such as to automatically throw the rest D' from the dotted to the full line position of Fig. 4. In this embodiment it will be observed that the platform of the rest bridges the joint between the sections, and may be found advantageous since in laying a lighted cigarette on the rest the ashes will not fall between the sections but will be caught by one of the sections. For the purpose of actuating the platform of the rest D' when the sections are closed a suitable cam or equivalent actuator 7 may be used.

From Fig. 5 it will be observed that the base E' which carries the rest D' is adjustable. In the example shown the adjustability is effected by employing two sections 8 and 9 which are telescopically interfitting so that one section is movable relative to the other to match boxes or receptacles of various size. To facilitate the positioning of the base in a box or receptacle the ends of the members of the base are preferably made of flattened or wedge-shape formation to readily fit into a depression, or beneath a rim portion of the box or receptacle. Various manufacturing expedients may be resorted to in effecting the adjustable base, but a practical embodiment is suggested in the drawings wherein the member 8 is a channel member and the member 9 is a strip frictionally held therein in such a manner as to enable one section to be held relatively

set to the other when positioned for use. As shown, the side edge portions of the member 8 may be struck up to provide the eyes 11 for receiving the bail members which support the rest D', and if desired, certain of the eyes 11 may be provided with stop projections 12 for limiting the movement of the rest under the influence of the spring 13, thereby to hold the rest in its proper elevated position. This construction provides a self contained rest or support for the lighted cigarette when sold for use in connection with receptacles having other contents at the time of the original sale, for example.

In use, the section A constitutes an ash tray, although it will of course be understood that ashes may be placed in either section, and either section may be regarded with reference to the other as a cover.

In connection with the rest or rack D, or its equivalent, it may be pointed out that the plate or platform portion thereof is preferably formed with flutes or corrugations, or if desired the same may be perforated. In other words, the plate or rest is ventilated to prevent "sweating" of the cigarette, or rather the condensing of the nicotine on the support by permitting air to get beneath the burning portion of the cigarette, thus avoiding fouling of the rest.

Another distinctive advantage of the invention resides in the provision of a receptacle which may be made air tight so that when a lighted stub is enclosed therein it will be quickly extinguished. In other words, it is proposed to provide a tight fitting receptacle so that when the oxygen content thereof is burned out by the lighted stub, no further combustion will take place. Experience has shown that this requires only a few seconds, thus avoiding the heating up of the metal part of the box and also avoiding the obnoxious smoke frequently incident to the complete burning of cigarette stubs.

From the foregoing it will be apparent that the present invention provides a safe, practical, and convenient pocket ash tray or receptacle which not only makes an attractive article for personal use but encourages cleanliness and avoids the burning of furniture and the like by the careless disposition of ashes and lighted stubs.

Without further description it is thought that the features and advantages of the invention will be readily apparent and it will also be understood that changes in the form, proportion and minor details of construction may be resorted to without departing from the spirit of the invention or scope of the appended claims.

I claim:—

1. A smoker's appliance including a receptacle comprising two cup-like sections,

- a hinge connecting said sections, a cigarette rest including a plate, a base member adapted to be fitted to one of the sections, means for swingingly connecting the plate and 40
5 the base member, and means for moving said cigarette rest from an elevated to a collapsed position and vice versa.
2. A smoker's appliance including cup-like sections, a hinge connecting said sections, a plate-like cigarette rest mounted in 45
10 one of said sections to move from a collapsed to an erect position in a plane at right angles to the hinge, and means carried by the other section for moving the
15 said cigarette rest to its collapsed position.
3. A smoker's appliance including a pair of cup-like sections, a hinge for connecting said sections and a cigarette rest carried by one of said sections and adapted to be 50
20 moved in a plane at right angles to said hinge to be erected for use, and a link connecting said cigarette rest and the opposite section.
4. A smoker's appliance including a pair of cup-like sections, a hinge connecting said cup-like sections, and a cigarette rest carried by one of said sections and including a relatively elongated plate whose longitudinal axis is arranged at right angles to 55
25 the axis of the hinge, a base member for connecting the rest to one of the sections, and means pivotally connecting the plate and base member whereby the plate may be brought from a nested position within the
30 section to an elevated position above the same.
5. In a smoker's appliance, the combination with a receptacle, of a cigarette rest 60
35
- comprising a plate and a base, means for pivotally connecting the plate and the base, and said base having adjustable means for engaging with the receptacle. 60
6. In a smoker's appliance, the combination with a receptacle, of a cigarette rest comprising a plate and a base, means for pivotally connecting the plate and the base, said base including telescopically interfiting members adapted to be extended to engage with one of said sections. 65
7. A smoker's appliance comprising a substantially air-tight receptacle providing a pocket ash tray and including interfiting sections hinged together, a rising and falling plate member constituting a cigarette rest carried by one of the sections and disposed at right angles to the axis of the hinge connection between said sections whereby the section opposite the one carrying the plate member may constitute an ash receiving receptacle. 70
60
8. A smoker's appliance including a receptacle comprising two cup-like sections, one of which constitutes a cover, a cigarette rest having a base member rigidly fitted into one of the receptacle sections, and a plate member provided with swinging supports connected with the base member and with the plate member, and means causing the automatic raising of the plate member with its supports upon the removal of the cover section of the receptacle, and for the depression of the plate member upon replacing said cover section. 75
70

In testimony whereof I hereunto affix my signature.

DANIEL W. CAUSEY.
